(57) **CLAIM**

I claim the ornamental design for an electronic device, as shown and described.

DESCRIPTION

FIG. 1 is a perspective view from the upper front right of an ornamental design for an electronic device; FIG. 2 is a perspective view from the upper rear left thereof; FIG. 3 is a front view thereof; FIG. 4 is a rear view thereof; FIG. 5 is a left side view thereof; FIG. 6 is a right side view thereof; and, FIG. 7 is a bottom view thereof.

The broken lines shown are included for the purpose of illustrating portions of the electronic device that form no part of the claim.
